his attorney.

UNITED STATES PATENT OFFICE

2,591,251

FLUORESCENT LIGHTING FIXTURE WITH
LIGHT BAFFLES

Louis Gilman, Brighton, Mass.

Application December 23, 1949, Serial No. 134,810

6 Claims. (Cl. 240—51.11)

1

The present invention relates to a fluorescent or other lighting fixture and in particular is an improvement over my prior Patent No. 2,475,233, issued July 5, 1949.

In the present invention, the fixture structure is principally formed of a single, stamped sheet providing substantially the same width and length of fixture as in the combination of the two halves from which the fixture of the prior patent is assembled. In the present invention, however, the improvement is not one of simply putting two halves together into one whole, but the structural design has been improved to provide a separating partition which automatically is locked in place when the fixture is given its permanent or final form. In addition to this, the construction of the supporting elements for the fixture which interlock with the fixture and the provision for the incorporation of the fluorescent light tubes provides a simple and efficient fixture which is remarkably easy to assemble and install and durable because of its peculiar construction.

Without further describing the merits and advantages of the present invention, the invention will be described in connection with the drawings set forth below showing an embodiment of the invention in which:

Figure 1 shows a development of a fragmentary portion of the fixture.

Figure 2 shows a side elevation of the fixture in its complete assembly with the right end broken away, and,

Figure 3 shows a section taken on the line 3—3 of Figure 2.

Referring to the drawings, Figure 1 shows the development of the fixture in a plane referred to the plane of the paper in which the forms of various parts will be referred to in the name of the elements of the ultimate structure. This comprises transverse baffles or plates 1 and 2 joined together through small tie strips 3 near one end of the plates and side sections 4 and 5 which form the sides of the fixture. The position of the fixture shown in Figure 2 as vertical, as for instance if it were hanging on a ceiling, shows the central baffle as for instance 2 positioned vertically, perpendicular to a central partition 6 which is also in a vertical plane. As indicated in Figure 3, the sides 4 and 5 are inclined upwards and outwards at an angle forming an enclosure or frame for the sides of the fixture. The central array of baffles 1 and 2 which are joined together by the short tie strips 3 are punched out with an oval or round-

2

shaped hole 7 which has a small neck opening 8 just above the tie strips 3.

The inner ends of the baffles 1 and 2 in their flat or developed form have end edges 9 and 10 respectively which diverge from the point of the throat 8 and terminate in inwardly extending tabs 11 and 12 which almost come together at their ends but which however leave a space between the ends which is equivalent to the throat opening at 8. This opening should be slightly wider than the thickness of the metal sheet of the partition 6. Just below the tie strip 3, the baffles are rounded off by a recess 13 giving the baffles the appearance of two independent elements rather than an element struck out from a single piece of metal. The form of the developed died-out structure is symmetrical with the center line O—O and the angle θ between the ends 9 and 10 and the center line O are not only equal but are such that when they are brought against the face 6 of the partition or nearly so, the top edges 14 and 15 of the baffles are horizontal or in the positions which are desired. The partitioning sheet 6 is provided with holes 16 through which the tabs 11 and 12 pass interlocking with one another. The partitioning element 6 is also recessed at spaced intervals at 17 at the bottom of the partition which are in line with the hole 16, and these recesses rest against the tie strips 3 with the inside walls of recesses coming against the sides of the tie strips if desired. There is, however, enough of a locking area since the partition 6 is locked in with every baffle sheet or plate and will therefore maintain firmly its position.

As described in connection with my prior patent, the baffle strips 1 and 2 are bent out of the plane of the paper as they appear in Figure 1 by counter-clockwise rotation as viewed from the right of Figure 1. Such a rotation will bring the lower side edges of the baffles as viewed in Figure 1 below the sides 4 and 5 and will put a 90° twist in the strips 18 connecting the baffles 1 with the side piece 4 and a similar twist in the strips 19 connecting the baffles 2 with the side piece 5. The side piece 4 will then be bent upwards about the strips 18 as a pivot in a counter-clockwise rotation as viewed from the lower end of Figure 1 and the piece 5 will similarly be bent upwards in a clockwise rotation to the position shown by 4 and 5 in Figure 3. The partitioning strip 6 may be inserted at this time or before if desired, and then the baffles may be forced downward until

the tabs 11 and 12 interlock in the hole 16 with the side edges 14 and 15 forming a continuation with one another if that is the ultimate form of the design. It will, of course, be noted that the upper and lower baffle edges need not be parallel to one another in the present design and these baffles may be shaped in different form than in the parallelogram form shown.

As described above, the fixture proper is formed and assembled. The only additional elements are the ends and the top which are readily applied as will presently be explained. The fixture is finished off at each end by an end plate 20 which is provided with flanged peripheral rims 21 at the sides of the plate and 22 at the bottom of the plate as well as flanges 23 and 24 which are inclined inwardly and terminate in a downward projecting hook-like elements 25 and 26. The flanges 21 lie in face contact with the ends of the side pieces 4 and 5 which may have turned in tip sections 27, 28 against which the flanges 23 and 24 rest. The end plates may be welded to the side plates or riveted or attached in any desired way.

The inturned hook sections 25 and 26 are engaged by a supporting hanger member 29 which is a part of the top cover or casing 30 in which the ballast units, wiring, support for fixture, fluorescent tube supports as shown by 31, 31 are all contained and supported. The cover 30 is provided with end sections 32 which may be a part of the cover 30 or attached to it in any way. The end sections 32 are provided with vertical end plates 33 which may have knock-out discs 34 for cables or conduit connections and which at its bottom edge has an inwardly inclined flange 35 which is integral with the supporting plate 29. It will be noted in Figure 2 that the end plate 20 of the fixture extends upward in the section 36 and covers the support 29. The cover member 30 is shaped in section as shown in Figure 3 and is provided at its end with a cover 37 welded to inwardly extending flanges 38 which are turned inward from the side walls 39 of the cover. The cover plate 37 supports the fixtures 31 for the fluorescent lights. The cover 30 together with the electrical fixtures for the lamps and the supporting end plates 29 are all assembled as one unit. A removable cover 40 serves to fit over the bottom of the cover 30 except for the end plate sections 37. This cover may be attached by machine screws or in any other suitable way and is removable so that the electrician can get at the inside of the fixture for attaching the cover 30 to the ceiling, making connections to the electrical wires and for other purposes. When the top section including the cover 30 has been fixed in position, then the rest of the fixture which has previously been described is put in place simply by hanging it over the supporting pieces 29. It will be evident from the description above that the fixture as a whole is very easy to install and further that it is readily removed for cleaning purposes since only the bottom section need be removed for this.

Having now described my invention, I claim:

1. A lighting fixture comprising an integral structure formed with side plates and a plurality of transverse baffle plates joined in aligned pairs

extending parallel to one another from one side plate to the other, connecting strips having a 90° twist joining each pair of baffle plates at their ends to said side plates, said twist permitting the baffle plates to be positioned in a vertical plane with the fixture horizontal, a connecting strip extending from adjacent ends of each baffle element of each pair connecting said baffles with a space therebetween, a central plate 10 extending lengthwise of said fixture filling said space and tab elements extending from said adjacent ends and engaging in holes in said central plate overlapping each other for fixing the central plate in place.

15. 2. A lighting fixture as set forth in claim 1, having end plates with flanges overlapping said side plates and providing hook-like supports extending transversely inward of said side plates and over the same and a top cover having downwardly projecting end plates engaging and interlocking in said flanges of said end plates.

20. 3. A lighting fixture formed with side longitudinal plates and parallel cross baffles joined at their ends to the side plates; an end plate attached at each end of the side plates and parallel to the cross baffles, said end plates having inwardly projecting flanges overlapping the side plates in which the end plates are secured to the side plates and extending inwardly beyond the 25 position of the side plates forming at each side of the end plate a hooked retaining flange; a covering box extending the length of the fixture having at its ends attached plates adapted to lie in face contact with the end plate and interlock with said hooked retaining flange to support said fixture suspended therefrom.

25. 4. A lighting fixture as set forth in claim 3 in which said attached plate is formed as a part of the end of said covering box and has an inwardly bent section where it joins the covering box permitting said attached plate to lie in face opposition with the inside of said end plate and the outside of said end plate to be in substantially the same plane as the outside of the 30 end of the covering box.

35. 5. A lighting fixture as set forth in claim 3 in which the parallel cross baffle plates are arranged in aligned pairs with adjacent end edges joined by thin strips to each other and to the side plates by thin strips with a 90° twist.

40. 6. A lighting fixture as in claim 5 in which the adjacent end edges of the baffle plates have projecting tabs engaging in holes in said longitudinal dividing plate and locking said longitudinal dividing plate in fixed position.
